UNITED STATES PATENT OFFICE.

ROLAND DRESSER DURFEE, OF LITCHFIELD, MICHIGAN.

PUMP-VALVE.

1,151,449.

Specification of Letters Patent.

Patented Aug. 24, 1915.

Application filed November 29, 1912. Serial No. 734,216.

To all whom it may concern:

Be it known that I, ROLAND D. DURFEE, a citizen of the United States, residing at Litchfield, in the county of Hillsdale and 5 State of Michigan, have invented a new and useful Pump-Valve, of which the following is a specification.

The invention relates to improvements in pump valves.

10 The object of the present invention is to improve the construction of pump valves, and to provide a simple, inexpensive and efficient pump valve of strong and durable construction, adapted to be readily applied 15 to an ordinary pump cylinder without necessitating a change in the valve seat, and capable of opening and closing without liability of wedging or sticking.

With these and other objects in view, the 20 invention consists in the construction and novel combination of parts hereinafter fully described, illustrated in the accompanying drawing, and pointed out in the claim here-to appended; it being understood that vari- 25 ous changes in the form, proportion, size and minor details of construction, within the scope of the claim, may be resorted to without departing from the spirit or sacrific- 30 ing any of the advantages of the invention.

In the drawing, Figure 1 is a vertical sectional view of a portion of a pump cylinder, equipped with a valve, constructed in accordance with this invention, the valve being 35 shown in elevation. Fig. 2 is a central vertical sectional view of the pump valve. Fig. 3 is a detail perspective view of the pump valve, the depending rod and the elastic disks being removed.

40 Like numerals of reference designate corresponding parts in all the figures of the drawing.

In the accompanying drawing in which is illustrated the preferred embodiment of the invention, 1 designates a pump valve constructed of suitable metal and consisting of a circular body having flat upper and lower faces 2 and 3 and provided at its periphery with integral guiding lugs 4, having 45 slightly curved outer faces adapted to fit the interior of a pump cylinder 5. The upper ends of the guiding lugs 4 are arranged in flush relation with the upper face 2, and the lower ends of the lugs terminate short of the lower face 3 of the valve, so that gravel or other accumulation

will not get beneath the lug and thereby interfere with the proper seating of the valve and cause the latter to leak. The lugs, which may have a straight vertical side face 6 at each side, are preferably provided with a slightly inclined face 7 at one side so that the water entering the cylinder will impinge against the inclined face 7 of the lugs 4 and cause a slight turning or rotary movement 65 of the valve to grind or wear the interior of the cylinder more evenly and thereby prevent any sticking or wedging of the valve in the opening and closing movements thereof.

The valve 1 is provided with a central vertical interiorly threaded socket 8, extending upwardly from the lower flat face 3 and terminating short of the upper face 2 so as to prevent any leakage at that point. 70 The socket 8 receives the upper threaded end 9 of a depending valve rod 10, which is screwed into the socket into engagement with the upper end wall thereof and which also extends through a central opening 11 75 of one or more elastic disks 12. The elastic disks 12, which may be constructed of leather, rubber, or any other suitable material, are secured on the rod by means of a nut 13, a metallic washer 14 being prefer- 80 ably interposed between the nut and the lower one of the disks 12. As the threaded rod abuts against the upper end wall of the socket, the nut 13 coacts with the threaded rod in locking the latter to prevent the 85 same from accidentally unscrewing. The disks are of the same diameter as the body portion of the valve, and the lower one fits against a valve seat 15 of a reducing coupling member or union 16, which connects the 90 lower end of the cylinder with lower piping, (not shown). By this arrangement the elastic disks are braced by the body of the 95 valve and there are no projecting portions to be easily broken. By terminating the 100 lugs short of the lower face of the cylindrical body, the lower portion of the latter forms a cylindrical extension, which effectually prevents the lugs from coming in contact with the valve seat and enables the 105 valve to operate effectively until the last valve disk is entirely worn away. Also the cylindrical body with the lower extension constitutes a weight, which holds the valve 110 close to the seat and prevents the suction of the pump from lifting the valve too high.

The lower end of the pump cylinder 5

is provided with exterior screw threads 17, which are engaged by interior screw threads 18 of the coupling or union 16, a washer or gasket 19 being interposed between the parts 5 at the valve seat to prevent leakage. The lower portion of the coupling member or union is provided with interior screw threads 20 to receive piping (not shown). In practice the rod 10 will preferably be 10 about eighteen inches in length and will extend down into the said piping. The rod provides a balance valve, which is guided in its upward and downward movement without liability of sticking, and the said rod is adapted to cause the valve 15 to drop flat against the valve seat and eliminate any tendency of the valve to turn edge-wise and prevents cramping or sticking of the valve.

20 What is claimed is:—

A pump valve comprising a substantially cylindrical body of a diameter to cover the valve seat of a pump cylinder and provided

with peripheral, radially outstanding lugs 25 having relatively broad outer faces curved in conformity with the inner face of the pump cylinder to which the valve is applied, with one of the side faces of each lug straight up and down and the opposite face slanting downwardly toward the straight 30 face, and said valve at the outer curved faces of the lugs being of a diameter substantially that of the inner diameter of the pump cylinder, and a single, free, elongated balance-rod 35 depending from the center of the valve and of a length to overcome the tendency of the valve to tip in its up and down movements.

In testimony that I claim the foregoing as my own, I have hereto affixed my signature 40 in the presence of two witnesses.

ROLAND DRESSER DURFEE.
